UNITED STATES PATENT OFFICE.

EDWIN HALL HUMPHREY, OF LANCASTER, PENNSYLVANIA, ASSIGNOR OF ONE-FOURTH TO HIMSELF, ONE-FOURTH TO ALICE HUMPHREY, AND ONE-HALF TO ABRAHAM B. KAUFFMAN, OF LANCASTER, PENNSYLVANIA.

DRAWERS-SUPPORTER.

No. 902,407.

Specification of Letters Patent.

Patented Oct. 27, 1908.

Application filed January 9, 1908. Serial No. 410,061.

To all whom it may concern:

Be it known that I, EDWIN HALL HUMPHREY, a citizen of the United States, residing at Lancaster, in the county of Lancaster and State of Pennsylvania, have invented a new and useful Drawers-Supporter, of which the following is a specification:

This invention relates to drawers supporters.

10 The object of the invention is to provide an article of this character which shall be simple in construction, efficient and durable in use, which, when positioned upon a pair of trousers, will be invisible, and which shall 15 be capable of being secured in place without the employment of stitches for the purpose, or any other extraneous fastening means.

With the above and other objects in view, as will appear as the nature of the invention 20 is better understood, the same consists in the novel construction and combination of parts, of a drawers supporter, as will be hereinafter fully described and claimed.

In the accompanying drawings, forming a 25 part of this specification, and in which like characters of reference indicate corresponding parts, Figure 1 is a view in perspective of the completed article. Fig. 2 is a vertical sectional view, on an enlarged scale, taken 30 through the waistband and lining of a pair of trousers showing the article assembled with the lining. Fig. 3 is a detail view of the blank from which the article is made.

The article is made from a strip of sheet 35 metal, preferably one that is resilient, and is stamped by appropriate machinery to the proper form, and comprises a head 1, a shank 2 provided with a prong 3, and a pin 4. The head 1 is preferably dished, although it may 40 be flat, if preferred, and is of greater width than the shank. The prong 3 is formed by stamping out a length of the metal for the purpose, and is preferably spear head shaped, and projects upward and away from the 45 head. The pin 4 is of the contour shown, or otherwise, and is curved at its point toward the shank and preferably rests thereagainst.

In constructing the article from the blank, after all the parts have been finished, the 50 shank is first bent to lie parallel with the head, or approximately so, and forms thereby a loop or bend 5 in which the drawers loop will rest, and is then rebent, forming a

second loop or bend 6, which will engage with the upper edge of the lining L of the 55 trousers waist band B, and the pin 4 will then have its point 7 curved toward the shank, thus to insure penetration of the lining L and will, by preference, bear against the shank. As will be noted, the prong 3 60 points upward, when the article is assembled with a pair of trousers, and thus in the direction opposite that of the pin, and operates to prevent the lining from working downward with relation to the shank, while 65 the pin holds the device assembled with the lining.

In positioning the supporter, the pin is inserted between the trousers band and the lining and is pushed down until the lining engages the bend 6, this procedure being effected by flexing the shank away from the pin. As soon as the shank is released, it springs 70 inward and forces the prong into the lining, and thereby completes the attachment of the 75 device.

It will be seen from the foregoing description that although the improvements herein defined are simple in character, they will be thoroughly effective for the purposes de- 80 signed, and will result in the production of a useful and highly effective article.

I claim:—

1. A drawers supporter comprising a head, a shank, and a pin, the shank being disposed 85 in approximate parallelism with the head and with a portion of the pin, and being provided with an upward projecting prong disposed towards the pin, the point of the pin being curved to lie close to the shank. 90

2. A drawers supporter comprising a head, a shank bent to lie approximately parallel with the head to provide a loop engaging bend, and a pin bent in approximate parallelism with the shank to provide a trousers 95 lining engaging bend, the shank being provided with an upwardly extending prong projected towards the pin and the point of the pin being bent toward the shank.

In testimony that I claim the foregoing as 100 my own, I have hereto affixed my signature in the presence of two witnesses.

EDWIN HALL HUMPHREY.
